UNITED STATES PATENT OFFICE.

FREDERICK R. WHITE, OF LYNN, MASSACHUSETTS.

HYDROCARBON-BURNER.

SPECIFICATION forming part of Letters Patent No. 684,487, dated October 15, 1901.

Application filed January 5, 1901. Serial No. 42,162. (No model.)

To all whom it may concern:

Be it known that I, FREDERICK R. WHITE, a citizen of the United States, and a resident of Lynn, in the county of Essex and State of Massachusetts, have invented an Improvement 5 in Hydrocarbon-Burners, of which the following description, in connection with the accompanying drawings, is a specification, like letters on the drawings representing like parts.

This invention has for its object the production of an improved apparatus for burning hydrocarbon oils whereby a pure fixed gas is first obtained from the vaporized hydro- 15 carbon, the pressure of such gas at the burner or point of ignition being practically uniform irrespective of the quantity which is permitted to pass to the burner, thus insuring a steady and perfect combustion at all times 20 and under all circumstances.

In the practical embodiment of my invention I first vaporize the liquid hydrocarbon and conduct the vapor to a superheater or gasifier, whereby the vapor is transferred into 25 a fixed gas, a pervious resistance being interposed between the vaporizer and gasifier to increase the pressure of the vapor before it enters the gasifier. From the latter the gas is admitted to a novel form of air-chamber, 30 at which point the requisite quantity of air is drawn in and mingles with the gas, the air and gas then passing to a mixer, in which they are thoroughly and most intimately mixed, after which such combustible mixture is ad- 35 mitted to the burner or burners.

The apparatus embodying my invention is very simple, durable, and quickly and easily controlled in its operation, and the construction is such that the parts may be easily taken 40 apart for cleaning, &c.

Various novel features of my invention will be hereinafter described, and particularly pointed out in the following claims.

Figure 1 is a top or plan view of one form 45 of hydrocarbon-burner embodying my invention, the drawing being partly broken out to show internal construction. Fig. 2 is a trans- 50 verse sectional view thereof on the line $x-x$, Fig. 1, showing the burner as applied to the combustion-chamber of a steam-boiler. Fig. 50 3 is an enlarged sectional detail showing the pervious resistance or retarder between the

vaporizer and gasifier and the controlling-valve for the latter. Fig. 4 is an enlarged detail, to be referred to, of the individual adjusting means for the valve-operating mechanism. Fig. 5 is an enlarged sectional detail, to be referred to, of the connection at the inlet end of the vaporizer. Fig. 6 is an enlarged longitudinal horizontal section on the irregular line x^2x^2 , Fig. 3, of a portion of the valve-actuating mechanism looking upward, the valve-controlling rod being shown in elevation. Fig. 7 is a transverse section taken on the line $y-y$, Fig. 1, looking toward the left to show the cross-brace B^5 and the relative positions of the brace, the burner-tubes, and the vaporizer, the parts at the left of the cross-brace, viewing Fig. 1, being omitted for the sake of clearness. Fig. 8 is a similar sectional view 70 on the line $y'y'$, Fig. 1, also looking toward the left, but not extending entirely across the apparatus; and Fig. 9 is a perspective detail of a portion of the chamber D^2 , to be herein-after referred to.

I have herein shown the burner as includ- 75 ing a plurality of units, and as the latter are alike only one will be hereinafter described in detail, it being understood that the opera- 80 tion of the burner is the same whether one or many units are employed, the capacity of the apparatus being of course increased by the addition of units.

In general form the burner is shown as rec- 85 tangular, (see Fig. 1,) and in Fig. 2 I have shown a part of the shell A of a vertical boiler extended downwardly at A' to form a combustion-chamber C^X , in which the burner is mounted, the crown-sheet A^2 , in which the lower ends of the flues A^3 are secured, form- 90 ing the top of such chamber.

A common distributor B is shown in Fig. 1 as extended the width of the burner, at one end thereof, supported on suitable brackets A^4 , Fig. 2, secured to the wall A' of the com- 95 bustion-chamber and attached to or forming part of the distributor, and communicating therewith are a series of mixing-chambers M , one for each unit, said chambers being herein shown as cylindrical and headed at their outer ends, as at m^X . By means of hollow nipples b , Fig. 1, burner-tubes $B' B^2$ communicate with and are attached to the distributor B , said tubes being arranged in parallelism and

having suitable burner-openings b^x therein, herein shown as saw-cuts. The tubes B' extend from one to the other end of the burner, and at their ends opposite the distributer I have shown them as connected by nipples or couplings b' with headers B^3 , the latter being also connected with the adjacent ends of the tubes B^2 , which extend only part way toward the distributer and are closed at their free ends.

The arrangement of the burner-tubes is such that each unit of the apparatus will include two of the shorter tubes B^2 , arranged adjacent and on opposite sides of the vaporizer, to be described, and two of the long tubes B' beyond the shorter tubes, the latter communicating with an intermediate adjacent tube B' by a header.

While I have shown separate headers, it will be manifest that a common header for the series of burner-tubes could be used, though for convenience in construction I prefer the separate arrangement.

Brackets A^5 support the headers, and the latter are secured to a cross-brace B^4 , while an inner cross-brace B^5 is secured to the inner ends of the short burner-tubes, said brace being shown in Figs. 1 and 7 as resting upon the long tubes B' at the extreme sides of the apparatus and notched at 300, Fig. 7, to straddle the interior tubes B' . The proper mixture of hydrocarbon gas and air passes from the distributer B to the burner-tubes B' , thence to the headers, and therefrom to the burner-tubes B^2 and is ignited at the openings b^x . The tubes B^2 are made shorter than the tube B' in order to provide space for the insertion of the means for superheating the gasifier of each unit, the length of the short tubes corresponding substantially with the length of the vaporizers.

I will now describe the construction and operation of the vaporizer, gasifier, air-chamber, and mixer of a unit of the burner, this part of my invention being of particular importance and value, as thereupon depends the success and effectiveness of the burner.

The vaporizer is shown as a tube V, internally threaded at its inner end at v (see Figs. 2 and 3) to receive the threaded boss c of a coupling C, an opposite boss c' being screwed into the preferably polygonal head g^x of a tube G, forming the gasifier or superheater, a longitudinal bore 2 through the bosses establishing continuous communication between the vaporizer and gasifier, and in Figs. 3 and 6 the bore is shown as enlarged to form a chamber c^x within the coupling C for a purpose to be described. The outer end of the vaporizer is provided with a coupling V' , communicating by a feed-pipe v' with a chamber V^2 , suitably connected with the supply of liquid fuel under pressure, (not herein shown and which may be of any desired character,) the chamber V^2 distributing the fuel to the several vaporizers, as shown in Fig. 1, the coupling V' having a threaded nipple v^3 ,

which is provided with a very small bore v^3 , (see Fig. 5,) and onto said nipple the threaded end of the vaporizer-tube V is tightly screwed, 70 said vaporizer having rigidly attached to it a head having a cylindrical portion 3 to fit in the opening in the wall A' of the combustion-chamber, Fig. 2, the head being made polygonal at v^2 to receive the jaws of a wrench. 75 The several couplings V' are secured to a supporting-bar 4, and the cross-braces B^4 and B^5 are provided with downturned notches 5, Figs. 2 and 7, to straddle the several vaporizers and prevent their lateral displacement, each vaporizer extending in parallelism with and between two adjacent short burner-tubes B^2 , Fig. 1, the length of the latter being substantially equal to that of the vaporizer, such tubes serving to heat and vaporize the hydrocarbon in the vaporizer. In order to prevent the free passage of the vapor and any of the liquid fuel to the gasifier, I interpose a pervious resistance medium v^x between the tubes V and G, such as asbestos fiber or any other suitable material which is permeable only by vapor under pressure greater than that due to the vaporization of the oil plus the initial pressure on the oil, and in order to prevent clogging of the passage 2 I have interposed a 95 guard v^3 , made as a conical coil of wire, its base resting against the threads v , and the resistance material v^x is packed around the guard, as clearly shown in Fig. 3. The resistance medium not only acts to prevent the 100 free flow of the vapor to the gasifier as rapidly as the fuel is vaporized, thus increasing the pressure of the vapor until it is high enough to overcome the resistance of the medium, but it serves to filter the latter and prevent 105 solid particles of carbonized matter from passing into the coupling C. The resistance medium being impervious to liquid and solid matter and permeable only by vapor under high pressure separates from the vapor generated in the vaporizer all particles of liquid and prevents the passage of any such particles to the gasifier, so that the vapor enters the latter in a dry condition to be gasified thereon. By locating the resistance medium 110 at the outlet end of the gasifier I am thereby enabled to provide a large and substantially unobstructed chamber formed by the main portion of the vaporizer for the vaporization of the liquid fuel therein. 115 At its outlet end the gasifier is threaded at g , Fig. 3, to receive a plug g' , having a valve-seat g^2 for a needle-valve g^3 , the threaded bore g^4 of the plug being flared at its inner end, and a gland g^5 is screwed into the bore 120 g^4 , the gland at its inner end having an aperture just large enough to permit sliding movement of the cylindrical stem of the needle-valve g^3 . Between the gland and the tapered mouth of the bore I insert a pervious 125 packing g^6 —asbestos fiber, for instance—and the gas enters the gland through inlet-ports 130 8, protected by the packing, the latter affording a resistance to the exit of the gas

- and maintaining the pressure in the gasifier. The needle-valve stem is connected by a coupling g^7 with a controlling-rod g^8 , loosely extended through the bore 2 of the coupling C 5 and projecting into the open space in the vaporizer beyond the guard v^3 , the rod being threaded at 9 to engage or pass through a threaded hole in a block c^2 , slotted at 301 to receive a wrist-pin c^3 within the chamber c^4 , 10 said wrist-pin being mounted on the headed end of a spindle c^4 , rotatably mounted in a plug c^5 , which is screwed into and closes the chamber c^4 , the spindle passing through a stuffing-box c^6 , screwed into said plug. The 15 slot 301 is transverse to the rod g^8 , so that circular movement of the wrist-pin by rotation of the spindle in one direction or the other will operate to move the rod g^8 in one direction or the other, the connection between 20 the spindle and the rod being of the well-known slot-and-pin connection. By rotating the spindle the actuating-rod g^8 will be moved longitudinally to open or close the valve g^2 , and by rotating the rod in said block 25 valve can be adjusted with great accuracy. The end of the rod is shown in Fig. 3 as threaded at 10 to receive a stop g^9 , having its end nearest the coupling C preferably made conical to enter the flared extremity 20 of 30 the bore 2 and stop the closing movement of the valve, as it is manifest that by adjusting the stop g^9 the valve may be made to just seat itself when the valve-actuating mechanism is operated to close the valve, and when 35 the valve is opened of course the stop will be withdrawn from the end of and will open the bore 2. The adjustable stop prevents the strain of shutting being transmitted to the needle-valve, the latter thus having to perform only its proper function—viz., the regulation of the size of the gas-outlet at g^2 , the stop 40 preventing any tendency to force the valve improperly into its seat, such forcing or jamming rapidly wearing both valve and seat. 45 The end of the plug g^7 projecting beyond the gasifier is inserted with a tight frictional fit into the head d of the air-chamber D, a flange 12 on the plug limiting the insertion into the chamber, and the projecting part of the plug is 50 preferably squared or polygonal to be readily engaged by a wrench. The plug and gland g^5 , with the packing, can be removed bodily from the gasifier when necessary for cleaning the parts, the needle-valve withdrawing 55 from the gland when the plug is taken out. I have found that a better and more uniform supply of air is provided and the latter will commingle in a more effective manner with the gas if the issuing jet of the latter is 60 injected into an enlarged closed chamber having an air-inlet non-adjacent to and at one side of the jet, the action being similar to that of an injector, a column of gas and air being forcibly discharged through a contracted outlet-port in the chamber located directly opposite the incoming jet of gas. 65 I have shown the air-chamber D as cylind-
- rical (see Fig. 8) and having a tapering or conical end d' , Figs. 1 and 2, to form a contracted outlet d^x , the latter being opposite the 70 gas-delivery opening g^2 . An elongated air-inlet tube d^2 is led into the side wall of the chamber, and herein it is shown as below the gas-inlet and somewhat beyond the latter, said tube d^2 communicating with the external air, and I have found it necessary to the proper operation of the apparatus that the air-inlet be tubular and elongated and of materially less cross-sectional area than the cross-sectional area of the chamber D. The 80 conical end d' has an annular seat d^3 , which fits tightly into the open end of the mixing-chamber M, so that the air and gas escape directly into the said chamber. The mouth of the throat d^x is so near the gas-outlet g^2 that 85 the jet of gas will rush across the intervening space in the form of a cone, the base of which meets and is contracted by the walls of the throat, adjacent the mouth thereof, filling the latter and tending to create a partial vacuum 90 in the chamber D, whereby fresh air is forcibly drawn into the chamber through the inlet d^2 and carried out through the throat by and with the jet of gas, a very uniform supply of air being provided, its quantity varying 95 according to the size of the gas-jet. The gas and air are forcibly discharged into the mixing-chamber M, wherein their mixture is thoroughly completed before passing to the distributor. 100
- I have provided heating means to act directly upon and raise the temperature of the gasifier sufficiently to rapidly convert the vapor entering from the vaporizer into a pure fixed gas free from moisture, the superheating means taking its supply of mixed gas and air from the mixer independently of the distributor or main burner device. 105
- Within the mixer I have mounted a hood H, having its inlet-opening h directly opposite 110 and quite near to the mouth of the throat d^x , and this hood has connected with it two pipes h' , which pass through openings in the ends of the air-chamber D and project beyond the head d thereof in close proximity to the gasifier, as clearly shown in Fig. 1, and a series of 115 burner-apertures h^x are made in the projecting pipes on the sides thereof nearest the gasifier, the extremities of the pipes or tubes h' being closed. The mixture of air and gas as 120 it forcibly issues from the throat of the air-chamber will pass into and fill the hood H and the pipes h' , keeping them filled all the time, the surplus or excess of the mixture passing into the mixer M. When the escaping 125 combustible mixture is lighted at the burner-openings h^x , the flame will impinge directly upon the gasifier G, raising the temperature of the latter to a high degree and changing the vapor entering therein into a 130 fixed gas, and whether the volume of the mixture ejected from the chamber D is large or small the hood and superheating burner-tubes h' will always be supplied with a suffi-

cient quantity to maintain a superheating-flame for the gasifier.

When arranging the apparatus to contain a plurality of units, as I have herein shown, I prefer to connect the various air-inlet tubes d^2 with a common air-inlet chamber D^2 , Figs. 1 and 2 and see also Fig. 9, extended beneath the main burner-tubes B' , said chamber being shown as recessed or horseshoe-shaped below the gasifiers, as at 30, Figs. 1 and 9, to facilitate the removal of any one or more of the gasifiers or vaporizers, said chamber D^2 being open along its inner end, as at 303, (see Fig. 9,) to admit the air thereto. The several couplings C are secured to upturned ears 40 on a cross-brace 42, extended from one to the other side of the apparatus, and which is upturned at its ends, as at 43, (see Fig. 8,) the said upturned ends being sprung into place between the two extreme outside burner-tubes B' . The several needle-valves of a multiple-unit apparatus must be operated simultaneously, and for this purpose I have provided the lower end of each rotatable rod c^4 with an arm c^{12} , carrying a set-screw c^{13} , passed through a segmental slot c^{14} in a second arm c^{15} , pivotally mounted on the shaft c^4 . The several arms c^{15} are connected by a common link c^{16} , and the latter is pivotally connected, as at c^{17} , at any convenient point with an operating-lever c^{18} , fulcrumed at c^{19} on a bracket c^{20} , depending from the cross-brace 42. All of the set-screws c^{13} being tightened, it will be obvious that each pair of arms c^{12} and c^{15} will move together, and longitudinal movement of the link c^{16} will rotate the several shafts c^{14} in one direction or the other to close the valves or open them simultaneously.

Frequently some one of the valves will not operate properly, no matter how careful the original adjustment may have been, and it will be necessary to vary the extent of rotation of its particular actuating-shaft c^4 . In order that such valve shall operate properly and to obviate the necessity of resetting all of the valves, I have provided the adjustable connection between the pairs of arms c^{12} c^{15} , as by loosening the set-screw c^{13} the arm c^{12} can be swung a little in one direction or the other relatively to its co-operating arm c^{15} to provide for the requisite adjustment of that valve, and thereafter the set-screw c^{13} is set up and the valve operated in unison with its fellows.

By means of the apparatus hereinbefore described I obtain perfect combustion and the flame burns with a clear blue color, no matter whether the valves are wide open or closed down sufficiently to permit just enough of the combustible gaseous mixture to pass to the burners to keep them lighted, and the combustion is effected without any disagreeable odor or smoke.

From the foregoing description of the apparatus it will be manifest that it can be readily taken apart when necessary for purposes of cleaning or to remove any accidental

obstruction, although by virtue of the previous resistance medium interposed between the vaporizer and the gasifier and between the latter and the outlet-opening it is very difficult for any solid particles to pass into the gasifier or to the valve-plug,

It will be noticed that I employ no check-valves or similar devices and that the communication between the vaporizer and gasifier is practically a continuous passage, although restricted; but the passage is uniformly restricted and not sometimes closed and sometimes open.

The pressure of the vapor is increased by the action of the resistance before the vapor is admitted to the gasifier, and the fixed gas generated therein is still further increased as to its pressure before escape from the gasifier by means of the superheater, which not only gasifies the vapor, but at the same time increases its pressure by means of such increased temperature.

My invention is not restricted to the precise construction and arrangement of parts herein shown, as the same may be modified or rearranged in various particulars without departing from the spirit and scope of my invention.

The burner embodying my invention is well adapted for use in automobile vehicles, as the flame can be turned down very low without decreasing the perfect combustion or putting out the fire.

To start up the apparatus when cold, the vaporizer can be initially heated by means of a small quantity of alcohol ignited in a trough-like receptacle F , (see Fig. 2,) placed beneath the vaporizer and gasifier, and as soon as a sufficient quantity of vapor has been generated to overcome the obstructed entrance it passes into the gasifier, the normal action of the superheater will begin, and the rapid heating of the whole device be effected.

The small bore or inlet v^{32} permits the fuel in liquid form to pass into the vaporizer in sufficient quantity to be substantially vaporized at once, so that no liquid collects in the vaporizer, and the small bore also enables the pressure of the vapor to be raised above that in the main supply-tank without creating any improper back pressure.

Having fully described my invention, what I claim as new, and desire to secure by Letters Patent, is—

1. In apparatus of the class described, a vaporizer, a gasifier in continuous communication therewith, and a resistance medium located at the outlet end of the vaporizer, impervious to liquid and permeable only by vapor under high pressure, to thereby raise the pressure of the vapor before it can pass to the gasifier and also to absolutely separate from such vapor all particles of liquid and prevent the passage of any of such particles to the gasifier, whereby the vapor enters the latter in a dry condition to be gasified therein.
2. In apparatus of the class described, a

vaporizer, a gasifier, a connecting-coupling having a passage therethrough establishing continuous communication between the vaporizer and gasifier, and a resistance medium located at the outlet end of the vaporizer, impervious to liquid and permeable only by vapor under high pressure, to thereby raise the pressure of the vapor before it can pass to the gasifier and also to absolutely separate from such vapor all particles of liquid and prevent the passage of any of such particles to the gasifier, whereby the vapor enters the latter in a dry condition to be gasified therein.

3. In apparatus of the class described, a vaporizer, a gasifier in continuous communication therewith, by a passage, a guard within the vaporizer at its outlet end, to protect the adjacent end of the passage, and a resistance medium located at the outlet end of the vaporizer, impervious to liquid and permeable only by vapor under high pressure, to thereby raise the pressure of the vapor before it can pass to the gasifier and also to absolutely separate from such vapor all particles of liquid and prevent the passage of any of such particles to the gasifier, whereby the vapor enters the latter in a dry condition to be gasified therein.

4. In apparatus of the class described, an elongated tubular vaporizer having an inlet at one end for entrance of liquid hydrocarbon, the interior of the vaporizer presenting an unobstructed chamber, a gasifier in continuous communication with the outlet end of the vaporizer, a resistance medium located at the outlet end of the vaporizer, impervious to liquid and permeable only by vapor under high pressure, to thereby raise the pressure of the vapor before it can pass to the gasifier and also to absolutely separate from such vapor all particles of liquid and prevent the passage of any of such particles to the gasifier, whereby the vapor enters the latter in a dry condition to be gasified therein, and separate means to superheat the gasifier.

5. In apparatus of the class described, a gasifier, a removable plug in its outlet having a valve-seat and a tapering bore communicating with the seat, a chambered gland mounted in the bore and having an inlet, a valve to cooperate with the valve-seat, a valve-stem extended through and supported by the gland, and permeable packing inserted between the gland and the tapering wall of the bore of the plug, interposing a filter to prevent the passage of foreign matter to the interior of the gland through the inlet thereof.

6. In apparatus of the class described, a gasifier, having an outlet, a valve co-operating therewith, a vaporizer, a coupling connecting it with the gasifier and having a passage therethrough to establish communication between the vaporizer and gasifier, a valve-rod longitudinally movable in said passage and extended into the gasifier, a coupling to detachably connect said rod and the stem of the

valve, and means to actuate the valve-rod from the exterior of the coupling connecting the gasifier and vaporizer.

7. In apparatus of the class described, main burners, a vaporizer contiguous thereto, a gasifier in continuous but restricted communication with the vaporizer, means to mix air with the gas discharged from the gasifier, a distributor connecting the main burners and the mixing means, means to direct a superheating-flame upon opposite sides of the gasifier, and independent means to supply the superheating means with a mixture of gas and air.

8. In apparatus of the class described, a gasifier, an air-chamber having a closed end in communication with the outlet-port of the gasifier, the opposite end of the chamber being contracted to form a throat, the mouth of which is located directly opposite the gas-port, and an elongated tubular air-inlet for the chamber, entering its side wall between its closed end and the contracted throat, and nearer the closed end, the cross-sectional area of the inlet being materially less than the cross-sectional area of the chamber.

9. In apparatus of the class described, an air-chamber having one end contracted to form an elongated throat, a gas-inlet port in the opposite, closed end of the chamber directly opposite the mouth of the throat, and an elongated tubular air-inlet for the chamber between its closed end and the entrance to the throat of materially less cross-sectional area than the cross-sectional area of the chamber, the tubular air-inlet opening into the chamber at its closed end.

10. In apparatus of the class described, a cylindrical air-chamber closed at one end and having a gas-inlet in said end, the opposite end of the chamber being tapered to form an elongated throat the mouth of which is directly opposite the gas-inlet, and a tubular air-inlet opening into the chamber, between the closed end thereof and the flaring opening of the throat, and adjacent the closed end of the chamber.

11. In apparatus of the class described, an air-chamber having a contracted discharge-throat, a gasifier connected with the opposite end of the chamber, the said chamber having an air-inlet in its side, a mixing-chamber into which the throat extends, a hood in the mixing-chamber, having an opening opposite the mouth of the throat, and a superheater adjacent the gasifier and in direct communication with the hood.

12. In apparatus of the class described, an air-chamber having an outlet and separated gas and air inlets, the gas-inlet being located opposite the outlet, a gasifier connected with the gas-inlet, a mixing-chamber, main burners connected therewith, a hood in said mixing-chamber having an inlet near and opposite the outlet of the air-chamber, to receive air and gas therefrom, and a superheater ad-

jacent the gasifier and communicating directly with the hood, said mixing-chamber communicating with the air-chamber.

13. In apparatus of the class described, a 5 mixing-chamber, means to inject gas and air thereinto, a hood within the chamber, having an inlet disposed to receive a portion of the air and gas as it enters the chamber, a super- 10 heater connected with the hood, and a gasi- fier contiguous to and heated by the super- 15 heater and in communication with the injecting means.

14. In apparatus of the class described, a 15 plurality of units each comprising a vapo- rizer, a gasifier in continuous but restricted communication therewith, a mixing-chamber for air and gas, an air-chamber interposed between the mixing-chamber and the gasifier, and a superheater for the latter, commu- 20 nicating with the mixing-chamber, combined with a distributer in communication with the several mixing-chambers, series of long burner-tubes connected at one end with the distributer and arranged in parallelism, and 25 a series of short burner-tubes connected with the opposite ends of the said long tubes, the short tubes being arranged in pairs adjacent and on opposite sides of the several vaporizers.

30 15. In apparatus of the class described, a plurality of units each comprising a vapo- rizer, a gasifier in continuous but restricted communication therewith, a mixing-chamber

for air and gas, an air-chamber interposed between the mixing-chamber and the gasifier, 35 a superheater for the latter communicating with the mixing-chamber, and a valve to control the passage of gas from the gasifier to the air-chamber, combined with a distributer in communication with the several mixing-cham- 40 bers, series of long burner-tubes connected at one end with the distributer and arranged in parallelism, a series of burner-tubes connected with the opposite ends of the said long tubes, the short tubes being arranged in pairs 45 adjacent and on opposite sides of the several vaporizers, and means to simultaneously open or close the several valves.

16. In apparatus of the class described, a common distributer burner-tubes connected 50 therewith, a plurality of mixing-chambers communicating with the distributer, a plurality of gasifiers, each having a controlling-valve to govern the issue of gas therefrom to the mixing-chamber, means to operate the 55 valves simultaneously, and an adjustable connection between each valve and said actuating means, whereby any valve may be adjusted independently of its fellows.

In testimony whereof I have signed my 60 name to this specification in the presence of two subscribing witnesses.

FREDERICK R. WHITTE.
